UNITED STATES PATENT OFFICE.

NEWELL SANDERS, OF CHIATTANOOGA, TENNESSEE.

DESIGN FOR A PLOW-STANDARD.

SPECIFICATION forming part of Design No. 27,077, dated May 18, 1897.

Application filed March 22, 1897. Serial No. 628,785. Term of patent 14 years.

To all whom it may concern:

Be it known that I, NEWELL SANDERS, a citizen of the United States, residing at Chattanooga, in the county of Hamilton and State of Tennessee, have invented and produced a new and original Design for Plow-Standards, of which the following is a specification, reference being had to the accompanying drawings, in which—

10 Figure 1 is a front view of the standard; Fig. 2, a view of the left side; Fig. 3, a view from the opposite side, and Fig. 4 a plan view. Fig. 5 is a section on line xx of Fig. 1.

15 The leading feature of the design is in the general configuration of the standard, which when viewed from the front presents a flaring shape, receding upwardly and rearwardly to the left, the concavity being relieved by a depression along the lower edge and a second depression b along the right-hand edge. The up-

per view of the standard shows a rectangular top with a slope downwardly to the front and left-hand side, but overlapping the center of the standard on the right, thus forming a projection on the right-hand side, as at c , looking down on Fig. 4.

In Fig. 3 the rear of the standard is curved from top to bottom, terminating with the front line in a point, and the face of the standard is recessed, as at d .

30 I claim—

The design for a plow-standard as shown and described.

In testimony whereof I affix my signature in presence of two witnesses.

NEWELL SANDERS.

Witnesses:

GEO. H. CURTIS,
E. M. ELLSWORTH.
